CARRYING CASE FOR A FLAT FOLDED
UMBRELLAHans Hoffmann, Essen, Germany, assignor to Telesco
Brophey Limited, Quebec, Canada

Filed Feb. 18, 1972, Ser. No. 227,697

Claims priority, application Germany Aug. 20, 1971

Term of patent 14 years

Int. Cl. D3—07

U.S. Cl. D87—1 R

FIG. 1 is a perspective view of a carrying case for a flat folded umbrella showing my new design;

FIG. 2 is a top plan view;

FIG. 3 is a front elevational view;

FIG. 4 is a bottom plan view;

FIG. 5 is a rear elevational view;

FIG. 6 is a left end elevational view; and

FIG. 7 is a right end elevational view.

I claim:

The ornamental design for a carrying case for a flat folded umbrella, as shown.
